UNITED STATES PATENT OFFICE.

PIERRE J. H. BERNARD, OF MONTREAL, QUEBEC, CANADA.

HEATER.

1,308,836.

Specification of Letters Patent.

Patented July 8, 1919.

Application filed October 22, 1918. Serial No. 259,174.

To all whom it may concern:

Be it known that I, PIERRE J. H. BERNARD, a subject of the King of Great Britain, residing at Montreal, Province of Quebec, 5 Canada, have invented certain new and useful Improvements in Heaters; and I do hereby declare that the following is a full, clear, and exact description of the invention, such as will enable others skilled in the art to 10 which it appertains to make and use the same.

The present invention relates to heaters and more particularly to an electric hot water heater or steam generator.

15 An object of the present invention is to provide a strong, durable and efficient heater of this character in which the various parts thereof may be assembled or taken apart should any of the same become worn or 20 broken, and new parts or sections may be easily and readily substituted and assembled.

With the above and other objects in view which will hereinafter appear as the description continues, the invention consists of the 25 novel features of construction, combination and formation of parts as will be herein-after more fully described and particularly pointed out in the appended claims.

30 In the accompanying drawings has been shown a simple and preferred form of the invention, it being, however, understood that no limitation is necessarily made to the precise structural details herein exhibited, but 35 the right is hereby reserved to any changes, alterations or modifications to which recourse may be had that come within the scope of the claims without departing from the spirit of the invention or sacrificing the 40 efficiency of the same.

In the accompanying drawings:

Figure 1 is a side elevation of the heater embodying the present invention;

Fig. 2 is a vertical cross section through 45 the same;

Fig. 3 is a detail cross section taken at right angles to Fig. 2;

Fig. 4 is a side elevation of one of the heating coils; and,

50 Fig. 5 is a front elevation of the same when one of the sections is removed.

Referring now more particularly to the accompanying drawings wherein like and corresponding parts are designated by similar reference characters throughout the several views.

The heater as herein shown comprises a base portion consisting of a circular plate 1 which is supported by means of the legs 2. Resting upon this plate 1 and detachably 60 connected thereto by means of the bolts 3 is a dome-shaped top or casing 4. Leading to the lower end of this casing 4 is an inlet pipe 5 and leading from the upper end thereof is an outlet pipe 6. A suitable gage 7 is arranged at one side of the casing 4, whereby when the heater is used for generating steam this gage may be brought in use for indicating the amount of water contained within the casing 4. Arranged within the casing 4 70 is a partition 8. This partition 8 is provided with a flange 9 which is retained between the ring 1 and the casing 4 and entirely closes the bottom of the latter. This partition extends up within the casing 4 and comprises 75 a plurality of compartments 10 which are opened at their lower ends. Adapted to be seated within these compartments 10 are the heaters 11 and each of these heaters comprises two sections 12 and 13 respectively. These sections 12 and 13 may be made of porcelain or similar refractory material and embedded within the section 13 are the coils 15 having the usual positive and negative terminals 16 which may be connected with a suitable electric circuit. These sections 12 and 13 may be connected by means of the set screws 17.

From the foregoing it is obvious that should any one of the sections 12 and 13 become broken or new coils should be replaced therein, the heater may be readily removed from the compartment 10, disassembled and new parts substituted for the worn or broken parts. The heater may then be readily inserted in place without disturbing the other parts of the device. Detachably connected to the lower face of the ring or plate 1 is a plate 18 having its inner edge adapted to project below the ends of the heaters 11, as 100 better shown in Figs. 2 and 3 of the drawings, whereby these heaters may be supported and retained within the compartments 10. In removing one of these heaters the plate 18 is first removed and then any 105 one of the heaters may be easily withdrawn from the compartments 10.

When current is applied to the heaters 11, water may be admitted through the pipe 5 where it will circulate around the compartments 10 of the partition 8 and subsequently rise and pass through the outlet opening 6.

When the apparatus is being used for generating steam, a small amount of water may be admitted to the casing 4 and the amount of water contained within this casing 4 may be 5 readily ascertained by means of the gage 7. The steam generated may pass off through the pipe 6.

Having thus fully described my invention, what I claim as new and desire to secure by 10 Letters Patent is:

1. In a heater of the character described comprising a base consisting of a supported ring, a dome-shaped casing secured to said ring, a partition extending up within said 15 dome-shaped casing, a flange formed with said partition, said flange being secured between said ring and said casing, a plurality of compartments arranged within said partition, a sectional heater resting within each 20 of said compartments, a plate detachably connected to said ring for holding said heaters within each of said compartments, and an inlet and outlet leading to said casing substantially as and for the purpose specified. 25
2. An apparatus of the character described comprising a base, a dome-shaped casing secured to said base, a horizontally extending partition secured between said base and 30 dome-shaped casing, said partition having a plurality of vertically extending compartments projecting within said dome-shaped

casing, heaters arranged within said compartments, a water inlet and outlet leading to said dome-shaped casing, and means for 35 supporting said heaters within said compartments.

3. A heater of the character described comprising a base, a casing supported by 40 said base, a partition arranged between said casing and said base, said partition comprising a plate, vertically and parallel arranged compartments formed with said plate and retained in spaced relation, and heaters arranged within said compartments. 45

4. A heater of the character described comprising a supporting base, a casing secured to said base, a partition arranged within said base and said casing, said partition having a plurality of compartments, the lower ends of said compartments being open, a heater arranged within each compartment, said heaters comprising two detachably connected plates, coils arranged between said plates, a ring secured to said base for supporting said heaters within said compartments, a water inlet and outlet communicating with said casing, and said partition adapted to separate the water contained within said casing from said heaters substantially as and for the purpose specified. 55 60

In witness whereof I have hereunto set my hand.

PIERRE J. H. BERNARD.
